UNITED STATES PATENT OFFICE.

ARTHUR LACEY COURT, OF SAN FRANCISCO, CALIFORNIA.

ORE CONCENTRATION.

Application filed October 25, 1918. Serial No. 259,634.

To all whom it may concern:

Be it known that I, ARTHUR LACEY COURT, a subject of the King of Great Britain, residing at San Francisco, State of California, have invented certain new and useful Improvements in Ore Concentration, of which the following is a specification.

This invention relates to apparatus for practising the froth-flotation process of ore concentration. Its object is to most efficiently, and economically and intensively carry on the said process, and with large plant capacity for a given available space. It relates to that type of froth-flotation apparatus wherein agitation and aeration are effected by the gravity flow of the pulp.

One adaptation of this invention is illustrated in the accompanying drawings in which:

20. Figure 1 is an elevation of two connected separators, showing their intervening aerator and the lower separator in midsection.

Figure 2 is a plan view of one of the separators, which may be taken on the plane 25 2, 2 of Figure 1.

Figure 3 is an elevation of an entire series of the separating vessels in operative relation.

Figure 4 is a plan view of the separator series of Figure 3.

The entire series of separating vessels shown comprises six of such vessels, vertically arranged. The number of such vessels would be varied as desirable in each case. They are shown as arranged in series, the pulp falling by gravity from separator to separator and froth overflowing from each vessel.

Each separator as shown comprises an outer sheet-metal casing consisting in upper and lower conical frusta 42 and 37 united by a short cylindrical section 41, and all carried by the annular angle-irons 39 and 40 bolted together by short bolts 54, and by long bolts 45 secured to the beams of the tower crib 6. The lower angle-iron 39 may be riveted to the lower casing section 37, and the upper angle-iron 40 may be riveted to the cylindrical section 41 which may in turn be united with the upper section 42 as a unit. The lower casing cone 37 is reinforced by a heavy inner liner 38 which takes the wear of the ore flowing through the separator, and discharges its tailings through a pipe nipple 17 connected

by a pipe flange with the flat bottom wall of the casing.

Inside each separator casing is an agitation bowl 33 supported on bolts 35 and spacing bushings 36 which also secure the liner 38 on the lower casing cone. This eddy bowl is formed with an upstanding conical center 34 merging into a stream-line continuity of bottom, sides, and re-entrant overhanging top. The intake pipe 28 of the separator is suspended in the vertical axis of its casing cones and eddy bowl so as to discharge the incoming pulp stream centrally upon the apex of the spreading cone 34. Within the upper casing cone, and upon the intake pipe 28 is mounted the grille 31 consisting in annular vanes connected by radial webs to a collar adjustably secured on the pipe by a thumb screw 32. Within the overflow mouth 53 of the upper casing cone, the froth crowder 29 is similarly mounted on the intake pipe by a thumb screw 30. A sheet-metal launder 43 surrounds the casing and discharges the overflow froth through the launder mouth 44 into the concentrates riser 51.

At its upper end the intake pipe 28 has a flange by which the pipe is suspended in the cap 27 screwed on the lower end of the cylindrical aerator 26 which is in turn suspended by a flange connection with the nipple 17 depending from the separator next above, or from the feed box 8 in the uppermost instance.

An interior flange 21 is formed in the aerator bore near its upper end to engage an upper shoulder 20 formed on the injector nozzle for the purpose of thus suspending the nozzle. The bore of this nozzle converges downward in stream-line formation to accelerate the pulp stream, but the lower or discharge mouth of the nozzle flares outward for the purpose of spreading the pulp stream to the area of the aerator bore so as to more efficiently propel the air downward therein while thus drawing air into the aerator through its inlet holes 23 just above the discharge mouth of the nozzle. The annular space between the nozzle and the aerator wall will receive the pipe 28 so that the latter may be lifted into the aerator and handled therewith as a unit.

Each separator casing has a by-pass outlet 55 leading through its middle cylindrical section 41 into a by-pass pipe 52 connect-

ed therewith by a pipe flange 46, the vertical web of the angle iron 40 being cut out to fit around this flange. This by-pass pipe 52 leads through a flow-regulating valve 14 into the aerator next in order, the connection to the aerator being made through a pipe-lug 24 formed thereon at or below the elevation of its nozzle discharge, and below its air inlet holes. In the case of the last 10 separator of the series, the by-pass pipe 50 leads through a corresponding flow-regulating valve 14, but discharges into the final tailings pipe 48.

The ore pulp suitably constituted and prepared for the required froth-flotation process of separation, e. g. by the addition of one or more mineral-frothing agents, is conveyed by a feed trough 5 into the feed box 8 having sufficient capacity to substantially equalize the flow of pulp therefrom, through the pipe 17 into the first aerator 26, and also over the overflow lip 10 and through the first by-pass pipe 12 into said first aerator. A wave baffle 9 prevents fluctuations in the overflow 20 at 10 which might be caused by an uneven delivery from the feed trough.

A valve 13 may be introduced into the first by-pass pipe 12, so that if desired it may be employed to regulate the pulp flow 30 through this by-pass and thus regulate the hydraulic head or liquid level in the feed box; or the pulp flow through this first by-pass pipe may be wholly unrestricted and the pulp level in the feed box maintained at 35 the level of the overflow 10 by determining the rate of feed through the trough 5 and the flow capacity of the feed box outlet 15 so that a continual excess flow from the trough will pass over the overflow.

40 In any event, the feed box delivers to the injector nozzle of the first aerator a substantially constant flow of pulp which is accelerated in the nozzle and discharged in a spreading jet which entrains the surrounding air while continuously drawing its air supply through the inlet holes of the aerator. The falling pulp and air are joined by the lesser pulp flow descending through the first 45 by-pass pipe 12, and the entire pulp and air column rushes violently downward through the inlet pipe 28 of the first separator, and is centrally delivered against the upstanding stream-line apex of the eddy bowl. The stream-line conformation of the eddy 50 bowl immediately translates the pulp fall into a hydraulic swirl in vertical planes radiating from the jet-spreading apex, which efficiently divides the falling pulp and breaks up the entrained air and mixes it into the pulp body in bubbles sufficiently minute and well distributed to effect the flotation of the certain mineral constituents required to be separated from the pulp by the phenomenon of froth flotation.

60 65 As the pulp is thus agitated in the eddy

bowl it continuously overflows the bowl, while the mineral-carrying air bubbles rise in the upper casing cone 42 and pass through the grille 31. The function of this grille is to cause a double deflection in the rise of the 70 air and mineral particles through it, so that the rise of gangue particles having less persistent buoyancy will not surmount this double change of direction but will fall back and leave the concentrate clean. The mineral-carrying bubbles are thus delivered from the upper side of the grille in a state of quiescent flotation rising by their buoyancy while being symmetrically crowded toward the center of the separator by the convergence of 80 its upper casing cone. As the bubbles rise into the overflow mouth 53 they form the mineral-bearing froth which is crowded outward toward its circumferential lip by the top crowder 29, the annular froth-discharging space between this crowder and the overflow lip being suitably adjusted by raising or lowering the crowder on the pipe 28. The intake pipe 28 may be hung so low that its discharge end will surround the upstanding 90 apex of the spreading cone 34, and the space between this cone and the pipe orifice can be adjusted for best results by screwing the adjustment cap 27 up or down on the lower end of the aerator. The cleaning grille 31 should 95 also be adjusted for most efficient action by clamping it with the thumb screw 32 at the most advantageous elevation on the pipe 28.

100 While the agitation bowl delivers its overflowing mineral-carrying bubbles through the cleaning grille and the froth-discharging mouth 53, the main body of the pulp liquor with its unfloated mineral and gangue particles overflowing the bowl turns downward through the annular space between the bowl and the separator casing, the greater part of this pulp passing through the tailings outlet 17 into the injector nozzle of the aerator next in order, and a smaller part of the pulp and its lighter particles flowing 110 through the by-pass pipe 52 into the side connection of said next aerator. The outflow capacity of the tailings outlet 17 and its connected injector nozzle, and the outflow capacity of the by-pass 52 as adjusted 115 by the regulating valve 14, are so determined as to maintain in the separator that elevation of pulp level which will produce best results, and in the illustrated adaptation of the scheme this liquid level would be well 120 above the grille 31. In any event, it is apparent that the liquid level may be readily varied and adjusted by manipulating the regulating valve 14. Generally speaking the by-pass will carry a pulp flow much less than the pulp flow from the bottom of the separator through the next injector nozzle.

125 The pulp thus delivered from the first separator to the aerator next in order, is thereby aerated as before described, and deliv- 130

ered through the next intake pipe 28 to the next separator wherein it is again subjected to agitation and separation as in the preceding aerator, and so on through the entire series of separators, the last of which delivers both its bottom discharge and its by-pass discharge to the final tailings pipe 48. During this flow of pulp through the separator series, the mineral-carrying froth delivered by each separator to its concentrates launder 43 is thereby carried into the common concentrates riser 51 which conveys the concentrates from all the separators to the concentrates tank 7, or to any other suitable place.

The separators are designed to effect the most efficient hydraulic action and thereby minimize the required hydraulic head per separator so as to reduce the necessary hydraulic head for the plant to the least practicable elevation, which desideratum may be very important on level ground. The scheme is of course adapted either for general separation or selective flotation of specific ore constituents, in accordance with the principles of the art, and is intended broadly for all manner of froth-flotation separation.

Other adaptations of the invention may be devised by artisans and technicians, and some by the exercise of supplemental invention, but all within the general principles of the invention here disclosed and within the scope of the following claims:

I claim:

1. Apparatus for froth-flotation separation comprising a casing having a froth overflow and a tailings outlet, an eddy chamber therein open at the top and disposed below the liquid level in the casing, and means for delivering a falling column of ore pulp and air into the eddy chamber, the bottom of the eddy chamber diverging downwardly and outwardly from the place of impact of the falling column, so as to spread the falling column, and also comprising an extension to then turn the flowing pulp and air upwardly.

2. Apparatus for froth-flotation separation comprising a casing having a froth overflow and a tailings outlet, an eddy chamber therein having a swirling-stream-line conformation and an open top and disposed below the liquid level in the casing, and means for delivering a falling column of ore pulp and air into the eddy chamber in a direction to be translated into a pulp-agitating swirl by the said swirling-stream-line conformation of the chamber.

3. Apparatus for froth-flotation separation comprising a casing having a froth overflow and a tailings outlet, an eddy chamber therein open at the top and having a central upstanding stream-spreading conoid and a bottom and sides all merging into a common swirling-stream-line surface dis-

posed below the liquid level in the casing, and means for delivering a falling column of ore pulp and air centrally upon the apex of the stream-spreading conoid.

4. Apparatus for froth-flotation separation comprising a casing having a froth overflow and a tailings outlet, an eddy chamber therein open at the top and disposed below the liquid level in the casing, means for delivering ore pulp and air into the eddy chamber, and a quieting grille in the casing above the eddy chamber and below the froth overflow, and means for vertically adjusting the quieting grille.

5. Apparatus for froth-flotation separation comprising a separator casing having a tailings outlet and an upwardly converging upper body with a froth overflow, an eddy chamber therein having a closed bottom and open at its top and disposed below the liquid level in the casing, and means for delivering a falling column of ore pulp and air into the eddy chamber, the eddy chamber bottom diverging downwardly and outwardly from the place of impact of the falling column so as to spread the falling column.

6. Apparatus for froth-flotation separation comprising a separator casing having a tailings outlet and an upwardly converging upper body having a froth overflow, an eddy chamber having a closed bottom and open at its top disposed within the casing below its liquid level, a spreading cone forming part of the bottom of the eddy chamber, and means for delivering a falling column of ore pulp and air upon the cone.

7. Apparatus for froth-flotation separation comprising a separator casing having a tailings outlet and an upwardly converging upper body having a froth overflow, an eddy chamber having a closed bottom and open at its top and disposed within the casing below its liquid level, a spreading cone forming part of the bottom of the eddy chamber, means for delivering a falling column of ore pulp and air upon the cone, and a quieting grille within the upper body of the casing and above the eddy chamber.

8. A separator casing having a tailings outlet and an upwardly converging cone-like upper body with a concentric froth overflow, an eddy chamber symmetrically disposed in the separator casing concentric with its cone-like upper body and having an open top likewise concentric and disposed below the liquid level in the separator and having its bottom and sides curved in swirling-stream-line formation, and a vertical intake pipe concentric with said cone-like casing part and the eddy chamber and arranged to discharge a falling column of ore pulp and air centrally into the eddy chamber in the line of origin of its stream-line swirls.

9. A separator casing having a tailings

outlet and an upwardly converging cone-like upper body with a concentric froth overflow, an eddy chamber symmetrically disposed in the separator casing concentric with its cone-like upper body and having an open top likewise concentric and disposed below the liquid level in the separator and having its bottom and sides curved in swirling-stream-line formation, and a vertical intake pipe concentric with said cone-like casing part and the eddy chamber and arranged to discharge a falling column of ore pulp and air centrally into the eddy chamber in the line of origin of its stream-line swirls, and a quieting grille symmetrically surrounding the intake pipe between the eddy chamber and the froth overflow.

10. Apparatus for froth-flotation separation comprising upper and lower casing parts shaped as cone-like frusta and at their larger diameters connected to form a separating vessel converging upwardly to a froth overflow and converging downwardly to a tailings outlet, a vertical intake pipe concentrically entering the upper opening of the vessel and arranged to discharge a column of ore pulp and air below the liquid level therein, and a vessel constituting an eddy bowl concentrically supported in the vessel with an intervening annular space and arranged to centrally receive the pulp-and-air discharge from the intake pipe and having its bottom and sides curved in a swirling-stream-line form adapted to agitate said mixture to form a mineral carrying froth.

11. Apparatus for froth-flotation separation comprising a series of separating vessels at successive levels and each having a froth overflow, means for feeding pulp and air into the first vessel, a final tailings outlet for the lowest vessel, and for each other vessel a main tailings outlet conduit leading its pulp from a main outlet into the vessel next below under conditions adapted to entrain air into the pulp, and for a vessel above the lowest vessel a supplemental pulp discharge conduit leading from a submerged level regulating outlet at a substantial distance below the pulp level in said vessel and above said main outlet but discharging into the course of pulp flow therefrom.

12. Apparatus for froth-flotation separation comprising a series of separating vessels at successive levels and each having a froth overflow, means for feeding pulp and air into the first vessel, a final tailings outlet for the lowest vessel, and for each other vessel a main tailings outlet conduit leading its pulp from a main outlet into the vessel next below and including means responsive to the pulp flow therein to entrain air into the pulp, and for a vessel above the lowest vessel a supplemental pulp discharge conduit leading from an outlet at a substantial

distance below the liquid level in the vessel and above its said main outlet but discharging into the course of pulp flow therefrom.

13. Apparatus for froth-flotation separation comprising a series of separating vessels at successive levels and each having a froth overflow, means for feeding pulp and air into the first vessel, a final tailings outlet for the lowest vessel, and for each other vessel a main tailings outlet conduit leading its pulp from a main outlet into a vessel below under conditions adapted to entrain air into the pulp, and for a vessel above the lowest vessel a supplemental pulp discharge conduit leading from an outlet at a substantial distance below the liquid level in the vessel and discharging into the course of pulp flow entering a succeeding vessel by a main outlet conduit, and means in said supplemental discharge conduit adapted to regulate the flow therein and thus regulate the liquid level in the vessel from which said supplemental discharge conduit receives its pulp.

14. Apparatus for froth-flotation separation comprising a series of separating vessels at successive levels and each having a froth overflow, means for feeding pulp and air into the first vessel, a final tailings outlet for the lowest vessel, and for each other vessel a main tailings outlet conduit leading its pulp from a main outlet into the vessel next below and including means responsive to the pulp flow therein to entrain air into pulp, and for a vessel (above the lowest vessel) a supplemental pulp discharge conduit leading from an outlet above said main outlet but discharging into the said main conduit leading therefrom to the vessel next below.

15. In a flotation-concentration apparatus, a froth pulp separating chamber, a deflecting grille in said chamber consisting of concentric nested plates, each plate in the shape of a cone frustum.

16. In an ore flotation apparatus, a froth pulp separating chamber a deflecting grille in said chamber consisting of concentric nested plates, each made up of two cone frusta oppositely inclined whereby air and mineral particles rising therethrough will receive a double deflection.

17. Apparatus for froth-flotation separation comprising a casing having a froth overflow and a tailings outlet, an eddy bowl therein having a spreading cone in its bottom, and means for delivering a falling column of ore pulp and air upon the cone, the sides of said bowl curving upwardly from said cone and adapted to serve substantially as stream-line guides for the pulp and air.

18. Apparatus for froth-flotation separation comprising a casing having a froth overflow and a tailings outlet, an eddy bowl

- therein having a spreading cone in its bottom, and a pipe for delivering a falling column of ore pulp and air upon the cone, the sides of said bowl extending upwardly 5 from said cone and having an overhanging top extending toward the pipe, so that the cone and sides substantially form stream-line guides for the pulp and air.
19. Apparatus for froth-flotation separation comprising a casing having a froth overflow and a tailings outlet, an eddy bowl therein having a spreading cone in its bottom, and a pipe for delivering a falling column of ore pulp and air upon the cone, 10 the sides of said bowl extending upwardly from said cone and having an overhanging and reentrant top extending toward the pipe, so that the cone and sides substantially 15 form stream-line guides for the pulp and air.
20. Apparatus for froth-flotation separation comprising an inverted pyramidal casing having a froth overflow and a bottom tailings outlet, an eddy bowl therein above 25 the outlet and having a spreading cone in its bottom, and means for delivering a falling column of ore pulp and air upon the cone, the sides of said bowl curving upwardly from said cone and adapted to serve substantially 30 as stream-line guides for the pulp and air.
21. Apparatus for froth-flotation separation comprising a series of separating vessels at successive levels and each having a 35 froth overflow, means for feeding pulp and air into the first vessel, a final tailings outlet for the lowest vessel, for each other vessel a main tailings outlet conduit leading its pulp from a main outlet into the vessel next below under conditions adapted to entrain 40 air into the pulp, a wholly submerged level regulating outlet for each said other vessel arranged at a substantial distance below the pulp level in said other vessel and a conduit leading pulp from said level regulating outlet to the main tailings conduit for its vessel to deliver 45 said pulp with the main tailings outlet discharge to the next vessel.
22. Apparatus for froth-flotation separation comprising a series of separating vessels at successive levels and each having a froth overflow, means for feeding pulp and air into the first vessel, a final tailings outlet for the lowest vessel, for each other vessel a main tailings outlet conduit leading its pulp from a main outlet into the vessel next below and including means responsive to the pulp flow therein to entrain air into the pulp, a wholly submerged level regulating 50 outlet for each said other vessel arranged at a substantial distance below the pulp level in said other vessel and a conduit leading pulp from said level regulating outlet to the main tailings conduit for its vessel to deliver 55 said pulp with the main tailings outlet discharge to the next vessel.

In testimony whereof, I have affixed my signature to this specification.

ARTHUR LACEY COURT.
